UNITED STATES PATENT OFFICE.

FRANK C. BURTON, OF CHICAGO, ILLINOIS, ASSIGNOR TO GRIGSBY-GRUNOW CO., OF CHICAGO, ILLINOIS, A CORPORATION OF ILLINOIS.

DESIGN FOR A RADIOCABINET.

Application filed October 27, 1928. Serial No. 28,674. Term of patent 14 years.

To all whom it may concern:

Be it known that I, FRANK C. BURTON, a citizen of the United States, residing at 431 South Wabash Avenue, Chicago, Illinois, have invented a new, original, and ornamental

Design for Radiocabinet, of which the following is a specification, reference being had to the accompanying drawing, forming part thereof.

In the drawings,

Fig. 1 is a perspective view of my cabinet showing the doors in closed position and,

Fig. 2 is a fragmentary view showing the appearance of the front of the cabinet with the doors open.

I claim:

The ornamental design for a radio cabinet as shown.

FRANK C. BURTON.
